REFRIGERATING APPARATUS

Harry F. Smith, Dayton, Ohio, assignor to General Motors Corporation, Dayton, Ohio, a corporation of Delaware

Application September 28, 1937, Serial No. 166,134

8 Claims. (Cl. 62—116)

This invention relates to refrigerating apparatus and more particularly to means for opening refrigerator doors, holding the doors open and holding the doors closed, and also to means for opening and holding open other doors.

It is often desired to open refrigerator doors when one or both hands are filled with articles to be placed in the refrigerator. Some manufacturers have attempted to solve this problem by providing foot pedal operated latches, but such latches are relatively difficult to operate and the relatively great distance between the pedal and the latch makes the problem of cabinet construction rather difficult. Various types of mechanical push type latches have been designed, but these do not operate sufficiently easy to permit the easy opening of the door which is required when the hands and arms are loaded with articles to be placed in the cabinet.

It is an object of my invention to provide a form of latch means in which the door is readily opened with only a very slight pressure, and which is readily accommodated in the walls of the door and the cabinet.

It is another object of my invention to provide a latch means without moving parts.

It is another object of my invention to provide a simple means for holding a door closed and a simple means for opening the door which is operated by manually controlled electrical power.

It is a further object of my invention to provide a door with means for holding the door tightly closed, and means for holding open the door, and a means for closing the door, all of which may be readily controlled by a manual electrical switch.

It is another object of my invention to provide a means for controlling the attraction between a permanent magnet and an electromagnet.

Further objects and advantages of the present invention will be apparent from the following description, reference being had to the accompanying drawings wherein a preferred form of the present invention is clearly shown.

In the drawings:

Fig. 1 is a front view of a refrigerator embodying my invention shown with the door open;

Fig. 2 is a sectional view taken along the line 2—2 of Fig. 1;

Fig. 3 is a sectional view taken along the line 3—3 of Fig. 2;

Fig. 4 is a sectional view taken along the line 4—4 of Fig. 1;

Fig. 5 is a sectional view taken along the line 5—5 of Fig. 4;

Fig. 6 is a wiring diagram showing the wiring of the electrical system for holding the door closed, pushing the door open and holding the door open;

Fig. 7 is a sectional view taken through the cabinet at one of its hinges;

Fig. 8 is a wiring diagram of a modified form of the invention; and

Fig. 9 is a sectional view through a different type of a refrigerator cabinet showing a modified form of the invention.

Briefly, in Figs. 1 to 7, I have provided a refrigerator with an electromagnet located in the door and a permanent magnet in the door jamb.

When the electromagnet is deenergized, the permanent magnet will attract its core to hold the door closed. The hinge of the door is provided with a light spring for urging the door to closing position and within the cabinet adjacent the

hinge of the door, an electromagnet is provided for holding open the door. A push button is provided at the side of the door and a foot pedal operated switch is provided at the bottom of the cabinet, either of which will energize both of the

electromagnets. The energization of the electromagnet in the door will cause the electromagnet to assume like poles with respect to the permanent magnet, thereby causing a powerful repulsion between the two magnets to push the door open.

The second electromagnet is also energized either by the foot pedal or the push button as desired in order to hold the door open. When the push button and the foot pedal are in released position, both electromagnets are deenergized and the door is moved towards closed position by the light spring and held tightly shut by the action of the soft iron core of the electromagnet by the permanent magnet.

Fig. 8 shows a modification in which the electromagnets are used both in the door and in the door jamb. Fig. 9 shows a modification in which the permanent magnet is provided in the door and an electromagnet is provided in the door jamb.

Referring now to the drawings, and more particularly to Fig. 1, there is shown a refrigerator 20 provided with an insulated food compartment 22 and a machine compartment 24 below the food compartment. The machine compartment is provided with a sealed unit 26 containing an electric motor and a compressor directly connected to the electric motor for compressing refrigerant and for forwarding the compressed refrigerant to a condenser where the compressed refrigerant is

liquefied, thence forwarded to a cooling unit 28 which is located in the food compartment 22 for cooling the air and the contents of the food compartment. The refrigerant evaporates within the cooling unit 28 and is returned to the compressor. The compressor is supplied with electric energy from a power supply through an electric supply conduit 30 and a conductor 32. Also connected to the electrical supply conduit 30 is a transformer and an alternating to direct current converter 34.

The food compartment 22 is provided with an insulated cabinet door 36 which is pivotally mounted upon a pair of hinges, one of which is shown in Fig. 7 and designated by the reference character 38. The portion of the cabinet surrounding the door when in closed position is called the door jamb.

Heretofore, it has been customary to provide a mechanical latch upon the face of the door or within the door and a keeper upon or within the door jamb. Occasionally, some manufacturers have provided a foot pedal at the bottom of the door which was connected by rods to a trigger within the keeper which was capable of pushing the latch out of engagement with the keeper. At other times, some form of handle or tripping mechanism was provided either on the face of the door or upon the face of the door jamb. With any of these types of latches, there was always some difficulty in opening the door when the arms and hands were filled with articles intended for the food compartment. Some have proposed electromagnetic operated latches, but such latches are rather complicated, since the usual mechanical latch mechanism must be provided in addition to the electromagnetic means for operating the latch mechanism.

In my invention, I do away with the mechanical latch mechanism and merely use a set of magnets for holding the door in closed position and include at least one electromagnet to create a polarity like that of the other magnet in order to cause a repulsion between the magnets for pushing open the door. This repulsion may be made as powerful as desired and this will govern the force, and, therefore, the distance the door is swung open.

It is, of course, desirable to employ a permanent magnet as the magnet with which to hold the door in closed position, because no current is then needed to hold the door closed. However, in the past, it has been found impossible to cause sufficient repulsion between a permanent magnet and an electromagnet to permit them to be separated without an undue force being required to aid in the separation. I have found that this is overcome by fastening a soft iron member to a permanent magnet and locating this soft iron member so that it has a face which comes substantially into contact with the face of the electromagnet; and I have further found that a very powerful repulsive force between the electromagnet and the soft iron piece attached to the permanent magnet can be obtained by a relatively small amount of current passing through the electromagnet. In this way, it is possible to employ a permanent magnet for holding the door shut and to employ an electromagnet merely for pushing open the door. Therefore, only a small expenditure of electric energy is required by the door over extremely short periods of time.

In Figs. 2, 4 and 5 inclusive, there is shown an electromagnet 40 of the U-shaped type, which is mounted in the cavity 42 in the door frame 44.

This electromagnet 40 is fastened by a long screw 46 to a plate 48 which is fastened to the door frame 44 and extends over the cavity 42. This plate 48 is provided with apertures through which the core of the electromagnet may extend. The protruding faces of the electromagnet may be ground so as to provide a smooth face. This plate 48 is securely fastened to the door frame 44 and thereby firmly supports the electromagnet 40.

A soft iron piece, mentioned before, is designated by the reference character 50 and has a face 52 which extends into close contact with the faces of the electromagnet 40. These soft iron pieces 50 are firmly fastened to the faces of the U-shaped permanent magnet 54 by a thin plate 56 and by a bolt 58 which extends through the thin plate 56 and through a heavy wedge 60 which is lodged between the pole portions of the permanent magnet 54. In this way, the soft iron pieces 50 are tightly clamped to the faces of the pole portions of the permanent magnet 54.

The permanent magnet 54 is located within a cavity 62 provided for it within the insulation 64 and the door jamb or frame 66. The front edge 68 of the inner liner 70 which lines the food compartment 22 is separated from and insulated from the permanent magnet by a suitable gasket member 72. The soft iron pieces 50 are silver soldered or otherwise fastened to a brass plate 74 which is fastened to the door jamb frame by brass screws 76. This plate 74 is provided with slots which receive the brass screws 76 so that the location of the soft iron pieces and the permanent magnet may be adjusted. The cavity in the wall of the cabinet adjacent the door jamb is covered by a door molding 78 which is provided with apertures through which the soft iron pieces 50 extend from the faces of the permanent magnet 54.

The electromagnet 40 as shown in Fig. 6 is connected to an electrical circuit which extends from the alternating to direct current converter by the electrical conductors 90 and 92 which extend from the converter 34. From the conductor 92, another conductor 94 extends to a push button 96. Another conductor 98 extends to a foot pedal operated switch means 102 which is operated by a foot pedal 104. A conductor 106 is connected from the foot pedal switch 102 and connects to another conductor 108 which extends to the electromagnet 40. The push button 96 is also connected by a conductor 110 through conductor 106 and the conductor 108 to the electromagnet 40. The electromagnet 40 is also connected by a conductor 112 to the conductor 90. The push button 96 is preferably located upon the face of the door jamb adjacent the edge of the door so that it may be conveniently pushed immediately before opening the door. The foot pedal 104 and switch 102 is located at the bottom of the cabinet beneath the machine compartment 24. In order to connect the push button 96 and foot pedal 102 with the electromagnet, I have provided a set of spring contacts 118 and 118 in the conductor 108 for supplying energy to the electromagnet 40, and another set of spring contacts 120 and 122 in the conductor 112 for the same purpose. However, any other sort of suitable connection may be used if desired.

When either the push button or the foot pedal switch is closed, current flows from the converter through the electromagnet, thereby exciting the magnet to create poles like the poles of the per-

manent magnet 54. This causes a repulsion between the electromagnet and the soft iron pieces 50 which are fastened to the poles of the permanent magnet sufficiently powerful to push the door open. With merely this much of the apparatus employed, it is undesirable to use a closing spring and the door may be easily opened by either the push button or the foot pedal switch or both, and it will remain open until it is pushed shut. No force is required to hold the door open, and only the lightest kind of push is required to close the door, because as soon as the face of the electromagnet and the face of the soft iron pieces are within several inches of each other, the permanent magnet will attract the electromagnet and pull the door shut. This attraction, of course, increases as the faces become closer together and the door is held shut so tightly in this manner by its magnetic attraction upon the core of the electromagnet that it is very difficult to open the door without proper energization of the electromagnet.

However, in addition to this simple arrangement, I have connected a second electromagnet 130 to the conductors 90 and 106 so that this electromagnet is also energized whenever the push button 96 or the foot pedal 104 is moved to switch closing position. When this electromagnet 130 is employed, a closing spring 132 is also provided upon one or both hinges of the door. This closing spring should be very light, so that it may be easily overcome by the door opening push provided when the electromagnet 40 is energized. Only a light return spring is required to shut the door because it is not required to supply the force necessary to latch the door, because the latching is accomplished by the attraction of the permanent magnet for the core of the electromagnet, and this attraction pulls the door shut tight and holds it there.

The electromagnet 130 is lodged within a cavity 134 provided in the insulation and the door jamb frame in the cabinet. An armature 136 is provided to be attracted by the electromagnet. This armature comprises a lever pivoted upon a pin 138 having a projection 140 at its opposite end which is in contact with a spring retainer 142 provided at one end of the compression type coil spring 144. The opposite end of this spring 144 is provided with another spring retainer 146 which carries a pin 147 for engaging a notch 150 provided in the door hinge. When the electromagnet 130 is energized, the armature 136 is attracted to cause it to turn in a counter-clockwise direction about its pivot pin 138, causing its projection 140 to compress the spring 144 and, thereby, provide a spring force tending to push the door open.

According to the wiring system shown in Fig. 6, the electromagnet 40 is energized simultaneously with the electromagnet 130 so that at the same time the holding open means is effective, the door is released and given an opening push by the repulsion between the electromagnet 40 and the permanent magnet 54. This push, together with the force of the spring 144, pushes the door open sufficiently wide to obtain easy access to the food compartment. Both electromagnets remain energized as long as either the foot pedal or the push button switches are held closed. Thus, the doors may be held open by keeping one of these switches closed, and articles can very conveniently be placed in the refrigerator at this time. After the articles have been placed in the refrigerator, the switch which is

closed may then be permitted to open, so that both switches are now open, and both electromagnets deenergized. This permits the armature 136 to assume its retracted position and permits the spring 144 to return to its inactive position without opposition. The light return spring 132 then swings the door to closed position, and the door is then latched or held tightly closed by the attraction of the permanent magnet 54 for the soft iron core of the electromagnet 40.

In Fig. 9, a modification is shown in which a somewhat different refrigerator cabinet construction is employed, and an electromagnet 210 is provided in a cavity 212 in the insulation 214 and the door jamb frame 216 of a refrigerator cabinet 218. This electromagnet is connected to a direct current converter, similar to the converter 34, under the control of a push button 220 located upon a wall of the cabinet. A rather unusual type door 222 is provided and has a permanent magnet 224 concealed therein which is fastened to a pair of soft iron pole pieces 228, each having one end silver soldered to a plate 226 fastened by wood screws 230 to the door frame. The other end of each of the soft iron pole pieces extends in close contact with one of the pole pieces of the electromagnet 210 which project from the door jamb.

As in the other modification, the permanent magnet holds the door closed when the electromagnet is deenergized. When the electromagnet is energized by pressing upon the push button, like poles as the permanent magnet are excited within it causing a repulsion between the two magnets, pushing the door open. This set of magnets may be used with the electrical circuits shown in Fig. 6, or, if desired, it may be used with an electrical circuit like that of Fig. 6 without the electromagnet 130.

In Fig. 8, a wiring diagram is shown of another form of my invention, in which two electromagnets are employed instead of a permanent magnet and an electromagnet. In this form, the door is designated by the reference character 240, and is shown in dotted outlines, while the door jamb is similarly shown and designated by reference character 242. A direct current converter 244 provided with an alternating current supply through the conductors 246 supplies direct current at a low voltage through the conductors 248 and 250 to an electromagnet 252 located within the door jamb 242. This electromagnet 252 is constantly connected to the converter through conductors 254 and 256. A second electromagnet 258 is provided in the door and has its pole disposed in close contact with the poles projecting from the door jamb. This electromagnet 258 is supplied with electric energy through the conductors 260, 262 and 264 under the control of a push button switch 266.

The electromagnet 252, which is continuously energized, attracts the soft iron core of the electromagnet 258 in order to hold the doors in closed position. However, when the push button 266 is closed, the electromagnet 258 is also energized to excite like poles within the electromagnet 258 which causes a repulsion between the two electromagnets, pushing the door open. The direct current converter 244 may be connected in the electrical system of a refrigerator in the same manner as is shown in the modification embodied in Fig. 1. It may also be used with a second electromagnet for holding open the door as is shown in Figs. 6 and 7, and the foot pedal switch may be provided in parallel

circuit relation with the push button 286 in a manner similar to that shown in Fig. 8. Where two electromagnets are employed, it is not necessary to employ the soft iron pole pieces between the two magnets.

Thus, I have provided a means whereby a repulsion may be caused between a permanent magnet and an electromagnet, and I further have provided magnetic means for causing repulsion between the magnets to push the door open and I further provide means for holding open the door when desired. All of these may be accomplished merely by closing an electrical switch, and only a relatively small current of the low voltage is required, and where no return spring is provided and no holding open electromagnet is provided, the door may easily be returned manually with a very slight push. Thus, I have provided a very convenient means for solving the refrigerator latch problems.

However, my invention is applicable to many other purposes. The broadest aspect of my invention, the means for causing repulsion between an electromagnet and a permanent magnet, is capable of the widest kind of application in many different fields, and is not limited to its use upon doors.

While the form of embodiment of the present invention as herein disclosed constitutes a preferred form, it is to be understood that other forms might be adopted, all coming within the scope of the claims which follow.

What is claimed is as follows:

1. Refrigerating apparatus including a cabinet incorporating a cabinet member and a door member, a cooling unit for cooling the interior of the cabinet, an electrically operated liquefying means for supplying refrigerant medium to and for withdrawing the medium from the cooling unit, a magnet upon each of the members, one of said magnets being an electromagnet, said magnets being positioned to attract each other when the electromagnet is deenergized and to repel each other when the electromagnet is energized, said electromagnet being connected to the electrical system of the electrically operated liquefying means for supplying electrical energy to the electromagnet, and means for controlling the energization of the electromagnet.

2. Refrigerating apparatus including a cabinet incorporating a cabinet member and a door member, a cooling unit for cooling the interior of the cabinet, an electrically operated liquefying means for supplying refrigerant medium to and for withdrawing the medium from the cooling unit, a magnet upon each of the members, one of said magnets being an electromagnet, said magnets being positioned to attract each other when the electromagnet is deenergized and to repel each other when the electromagnet is energized, a converter connected to the electrical

system of the electrically operated liquefying means for supplying direct current to the electromagnet, and means for controlling the energization of the electromagnet.

3. The combination including a door member and a door jamb member for the door member, each of said members being provided with a magnet, one of said magnets being an electromagnet, and means for energizing the electromagnet to create repulsion between it and the other magnet for opening the door member.

4. The combination including a door member and a door jamb member for the door member, each of said members being provided with a magnet, and electrical means for controlling repulsion and attraction between the magnets for pushing the door member open and for holding the door member closed.

5. The combination including a door member and a door jamb member for the door member, each of said members being provided with a magnet, means for causing the magnets to assume unlike poles for holding the door closed, and electrical means for causing the magnets to assume like poles for pushing the door member open.

6. The combination of a door member and a door jamb member for the door member, each of said members being provided with a member of magnetic material, the first of said members of magnetic material being a magnet, the second of said members of magnetic material being located adjacent the face of the magnet when the door member is closed to enable the magnet to attract the second member of magnetic material for holding the door member closed, and electrical means for exciting a polarity in the second member of magnetic material like that of the magnet for causing a repulsion between the magnets for pushing the door member open.

7. The combination of a door member and a door jamb member for the door member, one of said members being provided with a permanent magnet having soft iron pole faces, the other of said members being provided with an electromagnet having its pole faces adjacent the pole faces of the permanent magnet when the door member is closed, said electromagnet having its poles arranged to produce when energized a polarity like that of the permanent magnet to cause a repulsion between the magnets to push open the door member.

8. The combination of a door member, and a door jamb member for the door member, each of said members being provided with electromagnets having adjacent pole faces when the door member is closed, said electromagnets, when energized, being arranged to provide a like polarity, and means for simultaneously energizing said electromagnets.

HARRY F. SMITH.
